US00D842321S

(12) **United States Design Patent** (10) **Patent No.:** **US D842,321 S**
(45) **Date of Patent:** **** Mar. 5, 2019**

(54) **ELECTRONIC DEVICE WITH GRAPHICAL USER INTERFACE**

(71) Applicant: **Apple Inc.**, Cupertino, CA (US)

(72) Inventors: **Menkerios B. Andemicael**, San Leandro, CA (US); **Daniel L. Carter**, Oakland, CA (US); **Alexander Charles Maclean**, San Jose, CA (US); **Wyatt R. Mitchell**, San Francisco, CA (US); **Diego Monzon Del Pino**, Cupertino, CA (US); **Leanne Smitt**, Campbell, CA (US)

(73) Assignee: **Apple Inc.**, Cupertino, CA (US)

(**) Term: **15 Years**

(21) Appl. No.: **29/618,018**

(22) Filed: **Sep. 18, 2017**

(51) **LOC (11) Cl.** **14-04**

(52) **U.S. Cl.**

USPC **D14/486**

(58) **Field of Classification Search**

(57) **CLAIM**

The ornamental design for an electronic device with graphical user interface, as shown and described.

DESCRIPTION

FIG. 1 is a front view of an electronic device with graphical user interface showing the claimed design; and,

FIG. 2 is a front view of an alternate electronic device with graphical user interface showing the claimed design.

The outer broken lines in the figures show an electronic device, or an alternate electronic device, and form no part of the claimed design. The other broken lines in the figures show portions of the graphical user interface that form no part of the claimed design.

1 Claim, 2 Drawing Sheets
